METHOD OF AND APPARATUS FOR THE MANUFACTURE OF FLAT BAGS AND ENVELOPES

Application filed July 12, 1929, Serial No. 377,779, and in Germany July 13, 1928.

The high efficiency of enveloping-making machines which work from the punched or cut-out blank according to the cylinder-folding system is not attained by any of the "flat-bag" machines hitherto known, nor has it heretofore been possible to employ cylinder envelope-folding machines also for the manufacture of "flat bags" by means of a mere change of adjustment and without time-consuming interchange of essential parts, although in view of their efficiency and their other advantages, the principal one of which is their rapid and simple adjustability from one size to another, this seemed very desirable, the more so since flat bags particularly find employment, as articles handled in large quantities, for the most varied purposes to an extent even greater than envelopes. It should be understood that by the term "bags" or "flat-bags" as used above and in the following description the article referred to is a flat paper or like bag or envelope of the well-known type in which the bottom flap is of short or narrow form and in which the side flaps are gummed to each other centrally of the article or to one side thereof, as distinct from the usual form of envelope in which the side-flaps are connected together solely by reason of their attachment to the comparatively deep bottom flap which is gummed over the two folded but unattached side-flaps.

This invention relates in the first place to a method of manufacturing flat bags with side or central gumming, by means of which and in consequence of its novel sequence of operations the high-efficiency cylinder envelope-folding machines of the well-known type are made applicable for the optional manufacture of envelopes or flat bags. Further objects of this invention are the provision of improved means and arrangements for such optional manufacture of envelopes and flat paper bags.

In the process of manufacture that is customary, in the case of envelopes, with the employment of cylinder folding-machines, the sequence of the operations is as follows: (1) drawing-in of the individual sheet or blank from the stack in a direction parallel

to the side folds, (2) straightening of the sheet, (3) creasing of the bottom fold and closure-flap fold, (4) folding over of the side flaps, (5) application of the gum for the gumming of the bottom flap, (6) folding over and gumming of the bottom flap, (7) folding over of the closure flap. This method of operation was not possible in the manufacture of flat bags on machines by means of which envelopes were also manufactured, because in the latter the conveyor and other devices and their distances apart were not adapted to the great differences in length in the individual sizes of bags and because, above all, the short lengths of the bottom flap and the closure flap in the case of bags did not admit of uninterrupted conveyance through the machine.

The method according to the present invention is characterized by the fact that the bag cut-out or blank that is withdrawn from the stack is drawn into the machine in its full length in the direction of the folds of the bottom flap and the closure flap, whereupon, after the blank has been straightened out, the following operations are performed in succession: (1) creasing of the two longitudinal or side folds, (2) folding over and creasing of the bottom flap and closure flap, (3) reopening of the two latter flaps, (4) application of the gum to the narrow longitudinal flap and to the bottom flap, (5) folding over of the wide side flap, (6) folding over of the narrow side flap and performance of the longitudinal gumming, (7) closing of the bottom and closure flaps and performance of the bottom gumming. This sequence of operations alone affords the possibility of employing, for the manufacture of bags cylinder folding machines which at the same time serve for the manufacture of envelopes. But in this connection difficulties arise also, namely at the drawing-in of the sheet from the stack in consequence of its wide in-draw edge, then at the straightening of the blank or cut-out piece because of the slight length of the short side flap, particularly in case of bags with side gumming and finally in the folding of the bottom flap, closure-flap, and side flaps, because in this process the bottom

flap and closure flap must be folded over at that point at which in the case of envelopes the folding-over of the side flaps takes place, and vice versa in the case of bags the side flaps are folded at that point of the machine at which the folding of the bottom flaps and closure flaps is performed in the case of envelopes. In the case of bags, accordingly, although these require the reverse sequence, the bottom flap and closure flap are folded before the side flap because of the limitation to the arrangement of the devices within the machine, as it is required for the manufacture of envelopes.

These difficulties are overcome in accordance with the present invention by the alteration of the existing means and by the provision of new contrivances; in that connection precautions have been taken to ensure that the alterations made shall not be obstructive in the preparation of envelopes and that the special contrivances may easily and rapidly be removed or thrown out of operation.

In the drawings there is illustrated by way of example a cylinder folding machine which is in its essentials well-known for the manufacture of envelopes and which, for carrying out the method according to the present invention, is equipped with the alterations and special contrivances for the manufacture of bags.

Fig. 1 is a side diagram of the machine;

Fig. 2 is a representation of the different stages in the manufacture of flat bags according to the method of this invention, the individual stages of operation being drawn in vertical projection under those points of the machine at which they are reached within the latter;

Fig. 3 shows, in vertical longitudinal section, the means for the separation of the sheet from the stack and for its drawing into the machine;

Fig. 4 shows the suction device in front view;

Fig. 5 shows the suction device looking from above;

Fig. 6 is a sectional view of the means for controlling the suction;

Fig. 7 shows the same in transverse section;

Fig. 8 shows the means for the straightening of the sheet;

Fig. 8a shows the positions of the sheet relatively to the means of Fig. 8;

Fig. 9 is a plan view showing the means for the reopening of the bottom flap and closure flap after their folding;

Fig. 10 is a side view partly in section showing the means for the formation of the longitudinal folds of the bag;

Fig. 11 shows the upper cylinder serving in the forming of the first longitudinal fold, seen in the direction of the arrow in Fig. 10;

Fig. 12 is a longitudinal section of the

lower cylinder for the formation of the two longitudinal folds of the bag, together with its head-piece;

Fig. 13 shows the cylinder-engaging face of the said head-piece;

Fig. 14 is a side view of the means for the final closing of the bottom flap and closure flap;

Fig. 15 shows the pressure rollers for the bottom flap and closure flap, looking in the direction of the path of the work-piece; and,

Fig. 16 shows the same rollers in side view.

The machine, together with its modifications and special means for the manufacture of bags is hereinafter described in the sequence of the operating process, from the drawing-in of the blank to the delivery of the completed bag.

In the stack 1 the blanks or cut-outs are so arranged that the edge of the wide side fold S (Fig. 2) is situated toward the machine, i. e., in the drawing toward the right, and the closure flap V toward the beholder. The suction device 2, whose angular movement is indicated in broken lines, (in Fig. 3) seizes by suction the lowermost blank in the stack 1 and bends it down against the cylinder a. With the cylinder a there cooperates a pair of aligned rollers a' arranged above it and on both sides of the suction device 2. Each of these rollers a' carries an elastic draw-in finger 3 rotatable about its own axis. Between the fingers 3 space is left for the passage of the suction device 2. When the latter has bent the blank down into the position shown in broken lines (at Fig. 3) the suction ceases and the blank is stripped from the suction device by the drawing in fingers 3 and is laid upon the cylinder a. This stripping of the blank from the suction device presents difficulties in case of the employment of the form of suction device ordinarily employed for envelopes where the triangular bottom flap is seized only at its point by the suction device and to avoid these difficulties the suction device is provided with a fluting which extends in the direction of the path of the blank, so that in the process of drawing by suction, there is formed between the lowest blank and the one above it (even while the suction device is still in contact with the stack) a small recess which corresponds to the fluting of the suction device, and into this recess in well known fashion a swinging tongue 24 (Fig. 3) is introduced for the support of the stack before the suction device moves downward with the blank that has been drawn by suction. Shortly before the suction device is applied to the next blank, this tongue 24 is swung out of the operative position. In case of the preparation of flat bags the suction device must be of substantial width, and if this device were made with a fluting of the type above-mentioned, the front edge of the blank, in consequence of its length, would be bent

upwards at both sides of the suction device and would have a curvature extending towards the rear so that the stripping off from the suction device by the draw-in fingers 3 would be resisted by the stiffened blank and the front edge of the blank would be wrinkled or torn. In order to remedy this drawback, the suction device 2 is given, in accordance with this invention, two intersecting flutings 5 with the axis of the one extending in the direction of the path of the blank and the axis of the other perpendicular thereto, i. e., parallel to the front edge of the blank piece; and furthermore the suction apertures 25 in the suction device are so arranged that one or more of them are situated at the lowest point of the first-mentioned fluting, namely as far as possible in the direction of the edge of the blank, and the others on both sides thereof at the 10 lowest point of the other fluting which extends parallel to the edge of the blank. Figs. 3 and 4 show the effect of this expedient whereby the fluting which extends parallel to the edge of the blank creates a curvature of 15 the sheet which extends along the edge of the blank and corresponds to the natural bending of the sheet in its being stripped from the suction device, which curvature prevents such a curvature of the sheet as has a stiffening action, while the fluting produces at the same 20 time, in the direction of the path of the blank, in consequence of the higher-situated central suction aperture 25, in the middle of the edge of the cut-out piece, a recess sufficient for 25 entry of the swinging tongue 24 between the blank drawn by suction and the one just above it.

In order, in the manufacture of bags to impart the described shape, by means of the 30 suction device, to the wide sheet that is to be drawn away by suction, particularly also in the case of thick papers, and in order to attain the bending away of the sheet with certainty, not only is it necessary to have a powerful suction effect, but this effect must set in suddenly with its full power at the moment when the suction device is applied against the lowest blank, and must remain fully in action until the end of the blank has been bent down 40 so far that it can be seized by the draw-in fingers 3 (Fig. 3). This purpose is served by the following arrangement.

The hollow shaft 26 (Figs. 6 and 7), to which the swinging suction device 2 is attached, has mounted thereon a sleeve 27 which fits closely on the shaft 26; and fitting closely upon the sleeve 27 is a junction piece 28 which effects the connection through the bore 29 with the suction piping leading to the pump. 45 The bore 29 in the junction piece 28 communicates with a groove 30 which extends in an axial direction. In the sleeve 27 there is provided an aperture 31, of the length of the groove 30 in the junction piece 28 and at the 50 same point as the latter, which aperture ex-

tends over a definite portion of the periphery of the sleeve. At a likewise identical point and for the same length the hollow suction-device shaft 26 has a slit 32. The sleeve 27 projects on one side beyond the junction piece 28 and there carries a sprocket wheel 33 that is firmly connected with it. On this side the sleeve 27 is secured against longitudinal displacement on the shaft 26 by means of a collar 35, and the junction piece 28 is thus secured on the sleeve 27 by means of the sprocket wheel 33. On the opposite side the sleeve 27 and the junction piece 28 bear against the machine frame 34. The sleeve 27 is driven by means of the sprocket wheel 33 in such manner that it makes one revolution for every blank fed to the machine. In consequence thereof, in case of correct mutual adjustment of the shaft 26, the sleeve 27, and the junction piece 28 and in case of suitable width of the sleeve aperture 31, the result is that at the moment at which the suction has to begin, the aperture 31 suddenly effects in its full cross-section the connection between the pipe-end bore 29 and the slit 32 in the suction-device shaft 26 and interrupts it again with equal rapidity at precisely the correct instant. In case of the employment of a rotating suction pump the suction is in this arrangement uniformly powerful during its entire duration, so that the shaping described above and a positive bending away of the sheets are insured.

As soon as the sheet has been laid by the draw-in fingers 3 upon the cylinder *a*, the latter commences to execute a partial revolution, so that the sheet, which is grasped between the draw-in fingers and the roller, is withdrawn from beneath the stack to the extent of this partial revolution, in which process it gets under the pair of rollers *a'*. In this manner the sheets are arranged in echelon or overlapping relation one above the other in conformity with Fig. 2, I and are formed into a row which travels step-by-step to the pair 105 of rollers *b*—*b'*, which run continuously, but with corresponding rate of speed, and from the latter at uniform speed to the rapidly running pair of rollers *c*—*c'*, by which the foremost blank is seized and entirely withdrawn 110 from the row of blanks and is then conveyed forward alone on its further course and may thus be subjected to the further individual operations, each successive blank being thus separated from the row and being conveyed 115 forward. The first of the said individual operation consists in the straightening of the blank, for which purpose the means shown in Fig. 8 is provided.

Between the last-named pair of cylinders *c*—*c'* and the succeeding pair *d*—*d'* there are provided two pairs of straightening fingers, a front pair 4 and a rear pair 5. Both are adapted to swing in such a way that they locate themselves in the path of the blank 120

and withdraw from it again. The straightening of the blank is effected in well-known manner by this means; the straightening fingers placing themselves into the re-entrant corners of the blank and, in so doing, correct any irregularities in position of the blank. For the purpose of adaptation to the individual sizes, the rear pair of straightening fingers 5 is displaceable in the direction of the path of the blank and is capable of being set, and so also, in like manner, is the pair of cylinders c—c'. The mode of operation of the entire straightening stage is well-known per se and is briefly as follows:

The pair of cylinders c—c' is adjusted in such a way that it conveys those re-entrant corners of the blank that are situated toward the front in the direction of the motion to within a very short distance of the front straightening fingers 4 which have been swung into its path. At the moment at which the blank has reached this position, the rear straightening fingers 5 reach into its rear re-entrant corners and push it ahead such a distance that all four fingers are situated exactly in the four re-entrant corners of the blank, by which process the straightening-out has been effected. Thereupon all four of the straightening fingers are swung back and the blank is thereby released. At the same moment the flap 38, which is built into a longitudinal recess in the cylinder d' (and which may be moved by means of an adjustable cam disk 37 so as to coincide with or lie within the periphery of the cylinder) grips the sheet and thus delivers it to the periphery of the cylinder, which cylinder d' has two adjustable creasing knives for the creasing of the bottom fold and the closure-flap fold in the case of envelopes and of the side-flap folds in the case of bags. For the purpose of this creasing the counter-cylinder d has a rubber coating. In the manufacture of bags, particularly in the case of those with lateral gluing, it is impossible within this straightening stage, in consequence of the narrow side flap S', to convey the blank through the pair of cylinders c—c' as far as a short distance in front of the front straightening pair 4, because the cylinders c—c' cannot be placed close enough to the rear pair of straightening fingers 5. For this reason, in the preparation of bags, the pair of cylinders c—c' is set in such a way that the leading side flap S of the blank is pushed so far between the pair of cylinders d—d' that, seized by a segment 36 which, according to this invention, is specially built into the cylinder d', it is conveyed ahead by this segment a distance which is equal in the case of all sizes and which suffices to bring the front re-entrant corners of the blank within a very short distance of the front pair of straightening fingers 4, as is done directly by the pair of cylinders c—c' in the case of the

manufacture of envelopes. From this point onwards the rear pair of straightening fingers 5 takes over, in this case also, the further conveyance for the purpose of straightening, and now there results, as above described, the creasing of the side-flap fold by the cylinder d', after the latter's flap 38 has come into action in the manner that has likewise been described.

On its further course the blank then gets between the pair of cylinders e—e', which feeds it to a device, which is well-known per se, for the folding over of the bottom flap B and closure flap V, in which device the two flaps are bent upward by so-called lifters 9 around adjustable bladelike folding-bars 8 and are folded over by slides 10. This folding over of the bottom flap B and the closure flap V, generally speaking, takes place too soon in the case of bag blanks, because these two flaps must come to lie upon the side flaps, which, however, in consequence of the adaptation of the machine to the manufacture of envelopes are not yet folded over; nevertheless the folding over of the bottom flap and closure flap is performed, firstly in order to utilize the devices which are already available in the machine and secondly because of the fact that the performing of this work only after the folding of the side flap has taken place would have to take place under more unfavorable circumstances, as will be apparent below. According to the present invention, therefore, the bottom flap and closure flap, after they have been folded over by the above-mentioned devices and have been pressed between the cylinder f and its adjustable counter-rollers f', are immediately folded back again. For this purpose there is provided beyond the cylinder f and its counter-rollers f', an adjustable pair of curving fold guides 40 (Fig. 9). Each of these guides 40, of which only that at the one side of the blank is shown in the drawings, immediately adjoins the bladelike folding-bars 8, and the pressing rollers f', which are indicated in broken lines at Fig. 9, are adjusted so close above the folds that the folding back of the flaps may even be commenced during the pressing process. The curving fold guides 40 are expediently attached to the bearing-arms of the adjustable counter-rollers g' of the intermediate cylinder g, because in consequence thereof, at the adjustment of the intermediate rollers g to a particular size, the adjusting of the curving fold guides 40 is also effected simultaneously. The construction of the curving fold guides 40 is well-known per se; they are situated at the entering side of the blanks under the flaps, and the slope of their upper surface increases more and more in the direction of the path of the blank in such a way that by the end of the loop it turns to the extent of 180° and that the flaps, which

follow the course of the helical shape, are again folded back completely into the plane of the sheet.

For the application of gum, which takes place simultaneously for the gumming of the bottom and for the longitudinal gumming, means are provided which are employed also in the manufacture of envelopes, and which consist of the gum container 45, the gum-dipping cylinder 46, the gum application cylinder 47, and the gummers 11 which are interchangeable on their shaft. The upper cylinder h' of the pair of cylinders $h-h'$ which takes over the blank after the application of gum has taken place also consists, as in the manufacture of envelopes, of cylinder portions, adjustable transversely to the path of the blank, with recesses in their periphery in order to prevent smearing of the gum. For the turning up of the leading side flap S on its creasing we employ the same swingable folding-elbow 14 as serves for the turning upward of the bottom flap in the case of envelopes.

The following pair of cylinders $i-i'$, to which the closing and pressing of the bottom flap are assigned in the manufacture of envelopes, has, in the case of bag blanks to attend solely to the closing of the first side-flap fold. In this operation a swinging folding-blade 15 aids, in the well-known manner, the proper entrance of the previously made crease between the pair of cylinders. The upper cylinder i' , in view of the exposed gum still lying upward for the bottom gumming 12 and the longitudinal gumming 13 as indicated in cross-hatching in Fig. 2, VII requires special means for the manufacture of bags. In the first place the application of gum on the bottom flap necessitates the employment of only a narrow cross-bar 48 (Figs. 10 and 11) for the creasing of the folds of the first transverse folding which takes place between this upper cylinder i' and its lower cylinder i . This cross-bar 48 must not reach further over the fold than is indicated in Fig. 2, VI by the dot-and-dash line, since otherwise a smearing of the gum on the bottom flap would result. Furthermore, for the same reason the conveyance by the upper cylinder i' must not go further than a short distance in front of the inner edge of the longitudinal gumming 13 on the still open side flap S'. The distance that the conveying is to cover is accordingly different according to the size of bag that is to be prepared at any particular time, and therefore the upper cylinder i' is composed of mutually adjustable segments 49 in such a way that two inner fixed segments 49 directly take over, in the case of all sizes, the conveyance that has been effected by the rail 48, while the conveyance is turned over by these to two additional segments 50 which can be turned on the shaft 51 and there-

by be correspondingly adjusted to the length of conveyance that is possible at any particular time, and can also be displaced laterally in adaptation to the length of the bag.

The two outer segments 50 accordingly 70 convey the blank in conjunction with the lower cylinder i as far as a short distance in front of the inner edge of the longitudinal gumming 13; since, however, the conveyance must proceed without interruption, there is 75 a need at this point also, in the manufacture of bags, of special means which are furthermore also necessitated by the shortness of the trailing side flap S' in the case of bags having lateral gumming. To begin with, it may be mentioned that in the case of cylinder folding-machines of the type here in question, as they have in particular come to be known in their essentials from German Patent 349,878, (United States Patent No. 1,376,906, November 15, 1921) the blank undergoes a reversal of its direction of motion beyond the pair of cylinders $i-i'$, in that a piece of sheet metal which can be raised and lowered, the so-called shut-off 16, blocks its 80 path when it comes out of the cylinders $i-i'$. It is thus placed upright against this shut-off 16 until the second longitudinal fold in the case of bags or the closure flap-fold in the case of envelopes has left the cylinder $i-i'$; 85 then the shut-off 16 moves upward and clears the path to the second upper cylinder i'' which cooperates with the cylinder i and is displaced to the extent of about 60°. Under this upper cylinder i'' the second side flap 100 S' receives its folding in the case of bags, the closure flap in the case of envelopes. Here again a folding-blade 17 assures the correct entrance of the creased fold between the cylinders $i-i''$. The conveyance of this second 105 fold to the upper cylinder i'' must accordingly be effected with the aid of the trailing flap, which alone is still situated under the cylinder $i-i''$, a procedure which is indeed possible in the case of envelopes, but not in the case of bags, particularly those having lateral gumming, because in that case the trailing side flap is too short. In accordance with the invention this difficulty is overcome by this means that the cylinder i is constructed as a suction cylinder, which acts in such manner, that it grips the gummed side flap S' of the bag by suction even at its passage between the cylinders $i-i'$ shortly before its 110 conveyance by the segments 50 of the cylinder i' ceases. The suction persists until the second longitudinal fold has been received under the cylinder i'' . Figs. 10, 12, and 13 show the construction of the suction cylinder i . It has in its interior a suction channel 120 52 which extends in the direction of its length and from which several suction apertures 52', arranged in a row, lead to the outer surface of the cylinder. The suction channel 52 is open on one end face of the cylinder, and 125 130

against this end face of the cylinder a stationary head-piece 53 is closely applied. This head-piece 53 has in its interior a completely encircling annular channel 55 for the conveyance of the suction air together with a segment-like suction aperture 56 which is located in the direction of the cylinder and is so situated that at the rotation of the cylinder i the termination of its suction channel 52 comes to coincide with the aperture 56 of the headpiece 53. By means of a short pipe section 54 the annular channel 55 is connected to the suction piping of a rotating air-pump. The adjustment of the headpiece 53 and the delimitation of its aperture 56 are effected in such a way that the suction channel 52 of the cylinder i arrives over the aperture 56 of the headpiece 53 at that moment when the suction has to commence and leaves it again when the suction effect is to cease. By means of this contrivance a conveyance of the second longitudinal fold from the cylinder i' as far as the cylinder i'' is attained with certainty even in the case of bags having very short side flaps.

At the passage of the work-piece between the cylinders $i-i''$, in which connection the gum application device 12 of the still unfolded bottom flap B is situated in the direction of the cylinder i , precautions must be taken to prevent a smearing of the gum on this cylinder. On one portion of its periphery, where the bottom flap B runs past, it therefore has a recess 57 which is dimensioned according to the largest size of bag that is handled and which is indicated in Fig. 10 by the broken line that extends concentrically with the line of the periphery of the cut-out piece.

Whereas envelopes leave the pair of cylinders $i-i''$ in an already completed state and may be conducted to the delivery stack, it is necessary in the case of bag blanks that beyond this pair of cylinders the bottom flap B and closure flap V, which flaps were, for the reasons stated above, opened again after the first folding, shall be folded over finally and the former gummed in the process. The path from the cylinders $i-i''$ as far as the delivery stack 23 is therefore, according to the invention, so arranged that in the manufacture of bags it is possible to perform upon it the final folding over of the bottom flap and closure flap and the gumming of the former, while it can be traversed without further operations by the completed envelopes. For this purpose the well-known conveyor wheels 20, which push the completed bags to the stack by means of cams 22, attached to them, upon tracks 21 laid around them; are so far distant from the pair of cylinders $i-i'$ that from the latter to them a slanting travel path is produced. This is formed by four cylinders k, l, m , and n , which extend clear through, and their adjustable counter-rollers $k', l', m',$ and n' . In the manufacture of envelopes these convey the completed goods directly to the

conveyor wheels 20 and their counter-rollers 20'; as soon as it has left these, it rests loosely between the conveyor wheels 20 and the curved guides 21 extending around them, where it is seized by the cams 22 of the conveyor wheels 20 and pushed to the delivery stack 23. For the manufacture of flat bags, on the other hand, there is provided beyond the cylinder k and its adjustable counter-rollers k' the means for the final folding over of the bottom flap and closure flap. In consequence of the turning over of the work-piece which took place at the cylinders $i-i'$, this folding over must be performed under the cylinders k, l, m , an arrangement which would be unfavorable because of the poor visibility, if the folds were not already prepared in advance; but since such is the case in the course of operations above described, simple folding-bars 18 and curving fold guides 19 of well-known construction and similar to those which were employed for the folding back of the two flaps are sufficient for this operation. In this connection the arrangement is such that on each side the curving fold guide 19 is adjustably fastened by means of a bar 58' to the bar 58 of the folding-rail 18 so that after a mutual adjustment of the two has once been made, the adjustment of both may be changed jointly in case of change of the size or the thickness of the paper, namely the adjustment of the height by means of a shifting of the bar 58 in the cross-piece 59 and the transverse adjustment by a shifting of the cross-piece 59 on the attachment rail 60. After the departure from this folding-back device, there occurs between the cylinder n' and its counter-rollers n the renewed pressing of the fold into contact and the gumming of the bottom flap.

The counter-rollers n for the pressing of the fold and for the gumming of the bottom flap must likewise be given a special form of construction in the case of the manufacture of bags. Whereas in the manufacture of envelopes these rollers are traversed by the completed envelopes namely in such a way that the fold edge of the closure flap which lies uppermost runs up against the rollers and that the side flaps are furthermore secured against displacement by the gumming of the bottom flap, in the case of bags the fold edges of the loose closure flap and the bottom flap which is folded over, but not yet finally glued, impinge vertically against the rollers n and in consequence thereof, in case of the employment of ordinary cylindrical rollers, displacements of the flaps resulting in the production of double folds might easily occur. This danger is present all the more since, with a view to the gumming of the bottom flap that is to be performed, the rollers n must not be firmly in contact with their counter-cylinder n' , but must rather, in conformity with the thickness of the paper, be placed a slight distance away from the latter. Consequently

they must receive from each arriving work-piece a new impetus to rotation, but at least be brought again to their proper speed of rotation. The impact that occurs in this process aids the above-mentioned detrimental effect with respect to the displacement of the flaps and the production of double folds. According to this invention there are employed, instead of ordinary cylindrical rollers, rollers which have a narrow cylindrical running-surface 51; adjacent to this they have a slightly conical portion 62 and next to this again a cylindrical portion 63 (Figs. 15 and 16). The cylindrical running-surface 51 rests permanently upon the counter-cylinder n' , and the rollers n are so adjusted that the fold edges of the bottom flap and closure flap, according to the thickness of the paper in each case, project more or less into the conical portion 62, for which circumstance the amount of the pressure necessary in the cylindrical portion 63 for the gumming is determinative. Grooves 64 which extend circumferentially and longitudinally in the latter prevent a displacement and squeezing-out of the gum at the pressing into contact of the bottom flap by means of the roller n of the side in question of the blank.

The now completed bag runs, in the same way as the envelope, in well-known manner between the conveyor wheels 20 and their counter-rollers 20', by which it is introduced into the space 65 between the conveyor wheels 20 and the curved guides 21 which are located around them. Here one of the three pairs of cams 22 which are attached to the conveyor wheels 20 seize it at its rear edge and push it through the space 65 until its rear edge has reached the level of the delivery table 66. At this moment it is pushed away from the pair of cams 22 by a swinging arm 67 or some other device and is laid against the rear surface of a second pair of conveyor wheels 68, of well-known construction, which have a wormlike action and which add it, as the last piece at any particular time, to the delivery stack 23.

The rapid conversion of the machine from the manufacture of envelopes to the manufacture of bags or vice versa is ensured from the fact that a great part of the mechanism provided for the production of bags may be retained without modification also for envelopes. These are: the rotating suction valve 27, the segment 36 of the cylinder d' , the construction of the cylinder i' with the cross-bar 48 and the segments 49 and 50, and that of the cylinder i as a suction cylinder. Accordingly all that remains is the changing of the suction device 2 and the throwing into or out of operation of the folding mechanism, viz: 40 for the reopening of the folded-over and pressed bottom flap and closure flap in the case of bags, and of the mechanism 18, 19 for the final closing of these flaps, as well as, finally, the changing of the gummers 11. These alterations, to which there must further be

added only the simple adjustment operations—universally necessary also in case the type of blank remains the same—for the transition from one size to another, impart to the machine that unrestricted high efficiency for the manufacture of bags by which it is characterized to a noteworthy extent in its employment for the manufacture of envelopes.

We claim:

1. A method for the manufacture of flat bags or other similar articles of the character described, which comprises moving the blank in a direction parallel to the bottom fold and to the closure-flap fold, then creasing the two side folds, then while conveying the blanks folding over, and re-opening the bottom flap and closure-flap, then applying the gum to the bottom flap and one side flap, then folding and gumming the side flaps, and finally refolding and gumming the bottom flap and re-folding the closure flap.

2. A method for the manufacture of flat bags, which comprises moving the blank in a direction parallel to the bottom fold and to the closure-flap fold, then straightening the blank, then creasing the two side folds, then folding over, pressing and subsequently re-opening the bottom flap and closure-flap, then applying the gum to the bottom flap and one side flap, then folding and gumming the side flaps, and finally refolding and gumming the bottom flap and re-folding the closure flap.

3. A method for the manufacture of flat bags, which comprises drawing the blank from a stack, in a direction parallel to the bottom fold and to the closure-flap fold, then straightening the blank, then creasing the two side folds, then folding over, pressing and subsequently re-opening the bottom flap and the closure-flap, then applying gum to the bottom flap and to one side flap, then folding and gumming the side flaps and reversing the blank, re-folding and gumming the bottom flap, then re-folding the closure flap, and finally delivering the completed bag.

4. A cylinder folding-machine for the selective manufacture of envelopes or flat bags comprising elements which serve to form the side folds in the case of bags and to form the folds of the bottom and closure flaps in the case of envelopes, and means for the adjustment of said elements to change from one class of goods to the other.

5. A cylinder folding-machine for the selective manufacture of envelopes or flat bags comprising rotary creasing means which serve to crease the side folds in the case of bags and to crease the folds of the bottom flap and the closure flap in the case of envelopes, and adjusting mechanism for adapting said means to suit either class of goods.

6. A cylinder folding-machine for the selective manufacture of envelopes or flat bags,

comprising means for forming the bottom flap and closure-flap in the case of bags and which serve to form the side flaps in the case of envelopes, and interchangeable means for adapting the machine to suit either class of goods.

7. A cylinder folding-machine for the selective manufacture of envelopes or flat bags comprising means for forming the side folds in the case of bags and the bottom and closure flaps in the case of envelopes, means for forming the bottom flap and closure-flap in the case of bags and the side flaps in the case of envelopes, means for the application of gum to the bottom flap and to one of the side flaps in the case of bags, and to the bottom flap only in the case of envelopes, and variable means for the adjustment of the machine to suit one or other of said goods.

8. A cylinder folding-machine for the manufacture of flat bags, comprising a suction device for the separation of the lowest blank from a stack, a suction surface in such device, two flutings of arcuate cross-section intersecting each other at right-angles in said surface, and a separate suction opening in each fluting, one of which flutings extends in the direction of the path of the blank and the other perpendicular thereto, to cause the blank to bend in two opposite directions.

9. A cylinder folding-machine for the manufacture of flat bags, comprising a suction device for the separation of the lowest blank from a stack, a suction surface in such device, two flutings intersecting each other in said surface, one of which flutings extends in the direction of the path of the blank and the other substantially perpendicular thereto, suction apertures so distributed in the flutings that at least one aperture is located, close to the front edge of the blank, in the middle of the fluting that is situated in the direction of the path of the blank and the others on both sides thereof at the lowest point of the other fluting.

10. A cylinder folding-machine for the selective manufacture of envelopes or flat bags, comprising a suction device for the separation of the lowest blank from the stack, a suction shaft for said device, a junction piece connected with the suction source, a sleeve located between the shaft and the junction piece and moved in unison with the blank, an aperture in said sleeve, a slit in said shaft and a groove in said junction piece, the slit and groove both registering with said aperture to supply suction to the device.

11. A cylinder folding-machine for the manufacture of flat bags comprising straightening means for the blank, a rotary member for withdrawing the blank from the straightening means, and means carried by the cylinder to effect the conveyance of the blank until engaged by said straightening means.

12. A cylinder folding-machine for the se-

lective manufacture of envelopes or flat bags comprising straightening fingers for the blank, a cylinder for withdrawing the blank from the straightening fingers, and a segment carried by the cylinder to effect the conveyance of the blank until engaged by said straightening fingers, in the manufacture of bags.

13. A cylinder folding-machine for the manufacture of flat bags comprising means for the creasing of the bottom flap and closure flap of the bag, and a pair of curving fold guides for reopening the bottom flap and closure-flap.

14. A cylinder folding-machine for the selective manufacture of envelopes or flat bags comprising pressure means for the creasing of the bottom flap and closure-flap in the manufacture of bags, and a pair of curving fold guides for opening the said bottom flap and closure-flap.

15. A cylinder folding-machine for the selective manufacture of envelopes or flat bags comprising a cylinder for the creasing of the first longitudinal fold in the case of a bag blank, a longitudinal cross-bar carried by the cylinder and extending the full length thereof for the creasing of said longitudinal fold, and two pairs of segments embodied in said cylinder, one of which pairs is stationary, while the other may be turned on the cylinder axis and displaced in the longitudinal direction of this axis.

16. A cylinder folding-machine for the manufacture of flat bags comprising two cylinders, a common cylinder cooperating with said cylinders and serving therewith for the performance of the two longitudinal foldings, and suction means embodied in the common cylinder for the forward conveyance of the blank from the first to the second of said two cylinders.

17. A cylinder folding-machine for the manufacture of flat bags comprising a lower cylinder, two upper cylinders serving for the performance of the two longitudinal foldings, and suction means embodied in the lower cylinder for the forward conveyance of the blank from the first upper cylinder to the second.

18. A cylinder folding-machine for the selective manufacture of envelopes or flat bags of the character described comprising two adjacent cylinders, a hollow cylinder cooperating with both said cylinders to serve in the case of bag blanks for the performance of the two longitudinal foldings, and suction means embodied in the hollow cylinder for holding the side flap of the blank and ensuring forward conveyance of the blank from one to the other of said adjacent cylinders.

19. A cylinder folding-machine for the selective manufacture of envelopes or flat bags comprising a hollow lower cylinder, two upper cylinders serving in the case of bag blanks for the performance of the two lon-

gitudinal foldings, and suction means embodied in the lower cylinder for holding the side flap of the blank and ensuring forward conveyance of the blank from the first upper cylinder to the second.

5 20. A cylinder folding-machine for the selective manufacture of envelopes or flat bags comprising finishing means for effecting the final folding in the manufacture of envelopes, conveyor wheels for the delivery of the
10 envelopes, sloping means comprising pairs of rollers located between said finishing means and said wheels, and folding and closing mechanism embodied in said sloping means for closing the bottom flap and closure flap in the case of bag blanks.

15 21. A cylinder folding-machine for the selective manufacture of envelopes or flat bags comprising a pressure roller, a cylindrical surface thereon, a cylinder engaging said 20 surface, an adjacent conical portion on said roller and a second cylindrical portion the latter of which has grooves which extend circumferentially and in the longitudinal direction.

25 22. A cylinder folding-machine according to claim 20 in which the said sloping means comprises a pressure roller, a cylindrical surface thereon, a cylinder engaging said surface, an adjacent conical portion on said 30 roller and a second cylindrical portion adjacent to said conical portion and having grooves which extend circumferentially and in the longitudinal direction.

35 In testimony whereof we have signed our names to this specification.

ALFRED WINKLER.
MAX DUNNEBIER.
